UNITED STATES PATENT OFFICE.

HUGH W. COLLENDER, OF NEW YORK, N. Y.

POOL-RACK.

SPECIFICATION forming part of Letters Patent No. 296,532, dated April 8, 1884.

Application filed February 13, 1884. (No model.)

To all whom it may concern:

Be it known that I, HUGH W. COLLENDER, of New York city, in the county of New York and State of New York, have invented certain new and useful Improvements in Pool-Racks; 5 and I do hereby declare that the following is a full, clear, and exact description thereof, reference being had to the accompanying drawings, making part of this application.

10 My invention relates to certain new and useful improvements in that kind of pool-racks which are adapted to discharge the contents of all the shelves rapidly and automatically into the tray, triangle, or other receptacle in 15 which the game-keeper carries the collected balls from the locality of the pool-rack to the table upon which they are to be placed for the game.

Heretofore various contrivances of the type 20 alluded to have been devised, in some of which the balls have been discharged from the series of shelves by inclining them and permitting the balls to run down through a raceway or through chutes, and in others of which the 25 balls have been supported upon projecting pins, from which they have been lifted and discharged by the action of a triangle or tray provided with fingers and adapted to be moved up over the face or front of the pool-rack by 30 the person holding said triangle.

My present invention consists, essentially, in a rack provided with supporting shelves or surfaces adapted to tip upwardly and forwardly at their rearmost edges, so as to throw the balls 35 out, and provided with an ascending device, which, when lifted up, operates to tip the shelves successively, and which also serves to carry any suitable triangle or other receptacle into which the balls are collected, and 40 to properly deflect the balls into said receptacle, all as will be hereinafter more fully set forth; and my invention further consists in certain details of construction, which, in like manner, will be hereinafter more fully 45 explained, and which will be more particularly pointed out in the claims of this specification.

To enable those skilled in the art to make and use a contrivance embracing one or more of the features of my invention, I will now proceed

to more fully describe the latter, referring by 50 letters to the accompanying drawings, which form part of this specification, and in which I have represented a pool-rack apparatus in which my invention is carried out in that form in which I have so far practiced it. 55

In the drawings, Figure 1 is a front elevation of my improved contrivance. Fig. 2 is an edge or side view of the same. Fig. 3 is a vertical section at the line *x x* of Fig. 1. Fig. 4 is a horizontal section at the line *y y* of Fig. 1, 60 and Fig. 5 is a detail view or partial vertical section at the line *z z* of Fig. 2.

In the several figures the same parts will be found designated by the same letter of reference. 65

As clearly illustrated, the rack proper is composed, simply, of two side pieces, A and B, a base-piece, C, a cap or top piece, D, and a back board, E, together with a series of horizontal shelves, F, arranged between the side 70 pieces A B, as shown, and pivoted to the outer faces of said side pieces and supported by bracket-like stops or projections *a*, which are arranged on the inner faces of the side pieces A B. Each of the shelves F is pivoted 75 at each end and near its front edge to the said side pieces of the rack, and is formed with a longitudinal depression or groove, *b*, in its upper surface, in which rest the balls placed upon the shelf, and in the vicinity of each end 80 of each shelf is arranged, on the inner faces of the side pieces A B, stop-pins *c*, the office of which will be presently explained.

G is a sliding or vertically-moving carriage, the side pieces G' of which engage with the 85 outer surfaces of the sides A B of the rack by means of vertical grooves *e* in the latter and projecting feathers *f* on the former, that engage with each other, as shown. Each of the sides A B of the rack has through it, near 90 its middle, a vertical slot, H, which comes about in line with the rearmost corners of the ball-supporting shelves F, and the side pieces G' of the vertically-moving carriage are provided, as shown, with angle-levers I, the inner 95 ends of the horizontal portions of which projects slightly beyond the internal faces of the side pieces A and B. These inwardly-projecting

ends operate, as will be presently explained, as lifters, when the carriage G is raised up, to to lift up or flip upwardly the inner edges of the pivoted shelves F, and to permit these inwardly-projecting points of the levers I to pass the inner portions of the ends of the shelves F during the descent of the carriage G. Said angle-levers I, which turn freely on their pivotal connections, are provided with suitable springs, which permit the proper amount of play or swing to the levers and return them always to their normal positions. The carriage G is provided, as shown, with inwardly-projecting guards J, arranged at each end, and with a deflecting-surface, K, which is preferably padded or cloth-covered, and which, together with the inner or back surface of the guards J, operates to receive balls discharged successively from the shelves F, and to guide or deflect the balls into any suitable receptacle which may be applied to the carriage G, which latter, as shown, is made with a sort of rectangular recess below the deflector K and between the fenders or guards J, adapted to receive the front or forward portion of a suitable and, preferably, rectangular receptacle intended to be applied to the carriage and adapted to receive the balls discharged from the rack.

30 The stop-pins c, which, as shown, are preferably arranged at both ends of the tilting or tipping shelves, are merely to prevent the shelf from being thrown over so far in discharging the balls that they might not return to their normal positions by gravity, and might, if suddenly tipped, throw the balls outward and forward with too much impetus.

In the operation of the contrivance so far described, and shown in the drawings, it will be understood that when it is desired to collect all the balls which may have been placed upon the shelves F the game-keeper simply first applies to the carriage G his tray or receptacle, and then, taking hold of said carriage, slides it, together with the combined receptacle, upwardly to a sufficient extent to pass the uppermost shelf on which any balls may have been stored, and that during the ascent of said carriage the inwardly-projecting ends of the angle-levers I will in succession strike and lift the rear edges of the shelves in such manner as to successively discharge the contents of said shelves over their front edges, and in such manner that the balls falling from the shelves will roll onto a deflector or padded receiving-surface, K, and will from thence descend a very short distance into the receptacle or tray, the forward portion of which (as already explained) has been placed by the game-keeper beneath the said deflector K. During the descent thus of the balls from the shelves onto the surface K, and thence into the ball receptacle or tray, the balls which may pass off near either end of a shelf will be prevented 65 from tumbling outside of the receptacle, and

will be guided or deflected toward the center of the latter by the inner or back surfaces of the guards or fenders J, and as the deflecting and receiving surface K slopes upwardly at each end, (and in rear of the fenders,) this guidance of the balls toward the middle of the receptacle will thereby be still further insured. After the ascent of the carriage G to the proper extent, and the collection of all the balls in the tray placed on said carriage, the latter is simply pulled down or allowed to descend to its former position, when the game-keeper removes his receptacle or tray and replaces the balls upon the table as usual, and the pool-rack is ready for reuse.

Of course, the conformation of the receiving, guiding, and deflecting surfaces of the sliding carriage, which is adapted to support or contain, temporarily, the tray into which the balls are to be collected, may be varied more or less, according to circumstances, and to correspond with the size, shape, and character of the receptacle or tray which may be preferably used, and other variations in the details of construction may be made without departing from the essential features of my invention. Some other sort of lifting-fingers might be employed, and as to the lifting or shelf-tipping devices, as well as the stops for regulating the extent of motion of the shelves, one set of such devices, instead of two, might of course be employed. I do not therefore wish to restrict my claims of invention to the precise details of construction herein shown and described; and I wish it to be understood, of course, that the main feature of my invention might be employed with more or less advantage in a contrivance not involving the other features of my alleged improvements.

What I claim as new herein, and desire to secure by Letters Patent, is—

1. In combination with a pool-rack or set of shelves adapted to receive the players' balls, and from which the balls may be successively discharged or thrown out, a carriage-like device adapted to slide up and down in front of the rack, and provided with means for guiding the contents of the shelves as successively discharged, and a suitable receptacle adapted to be placed within said carriage and receive the contents of the pool-rack, all substantially as set forth.

2. In combination with the side pieces, A, B, of a pool-rack, a set of hinged or pivoted shelves adapted to tip upwardly and forwardly at their rearmost edges, and suitable means for successively tipping said shelves so as to discharge their contents in succession, substantially as set forth.

3. In combination with a set of hinged or pivoted shelves adapted to tip upwardly and forwardly at their rearmost edges, suitable stops to prevent said shelves from turning too far, substantially in the manner and for the purposes set forth.

4. In combination with a pool-rack capable of discharging the contents of its ball-supporting surfaces automatically, a carriage adapted to receive the discharged contents of the 5 shelves, substantially as described, the said carriage being provided with means, as set forth, for deflecting and guiding the balls to- ward its middle, to insure their proper reception within any suitable receptacle carried by the said carriage, all substantially as set forth. 10
H. W. COLLENDER.
